(57) **CLAIM**

The ornamental design for a combined seat cushion and ottoman, as shown and described.

DESCRIPTION

FIG. 1 is a front, left, top perspective view of the combined seat cushion and ottoman showing my new design;

FIG. 2 is a front, left, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded front, left, bottom perspective view thereof;

FIG. 10 is a front, left, top perspective view of the combined seat and cushion and ottoman in FIG. 1, shown in a first configuration;

FIG. 11 is a front, left, top perspective view of the combined seat and cushion and ottoman shown in a second configuration; and,

FIG. 12 is an exploded, front, left, top perspective view of the combined seat and cushion and ottoman, shown in a third configuration.

The short dash-short dash broken lines in the figures illustrate portions of the combined seat and cushion and ottoman, that form no part of the claimed design. The long dash-short dash broken lines illustrate stitching and form part of the claimed design.

1 Claim, 12 Drawing Sheets
